UNITED STATES PATENT OFFICE

CHARLES W. THOMPSON, OF WOLLASTON, MASSACHUSETTS, ASSIGNOR, BY MESNE ASSIGNMENTS, TO STEINER SALES COMPANY, OF SALT LAKE CITY, UTAH, A CORPORATION OF UTAH

ROLL TOWEL CABINET

Application filed November 15, 1928. Serial No. 319,532.

This invention relates to a roll towel cabinet, particularly the kind designed to be attached to a wall.

One of the objects of this invention is to provide a simple, reliable, and inexpensive mechanism whereby the act of unwinding the roll of clean toweling also winds the soiled toweling. Another object is to provide means whereby the toweling is automatically withdrawn from sight when it is released after using. Another object is to provide a measured or limited portion of clean toweling for each user. Still another object is to make the cabinet in two sections so that the inner section alone may be replaced when it becomes worn or unsanitary, thereby saving the cost of the more expensive outer section which will outwear several inner sections. This arrangement also makes it easier to insert clean toweling as it provides more room for the hands between the various parts.

With the above and other objects in view which will more readily appear as the nature of the invention is better understood, the same consists in the novel construction, combination, and arrangement of parts herein-after more fully described, claimed, and illustrated in the accompanying drawings.

When my cabinet is equipped with the automatic take-up mechanism, some slight changes are made in it, and the drawings illustrate the cabinet with and without said mechanism.

Figure 1 is a vertical sectional side view of my cabinet without the automatic take-up mechanism, showing the soiled towel hanging in a loop below.

Figure 2 is a front view of my towel cabinet with the door opened, partly broken away to show the towel and winding stick, and showing part of the automatic take-up mechanism.

Figure 3 is a cross-sectional view taken on the line 3—3 of Figure 2 with the door closed, showing my towel cabinet equipped with the automatic take-up mechanism in its normal position when the toweling is not being used.

Figure 4 is a sectional view taken on the line 4—4 of Figure 2 with the inner cabinet pulled out for loading.

Figure 5 is a cross-sectional view taken on the line 5—5 of Figure 3.

Figure 6 is a view in cross-section on the line 6—6 of Figure 4.

Figure 7 is a view in perspective of the traveler.

Figure 8 is a view in perspective of the winding stick.

Figure 9 is a front view showing one end of the sheet of toweling with the winding stick 60 inserted in the loop.

Figure 10 shows two lengths of toweling joined together with a clasp.

Like numerals and letters of reference indicate corresponding parts in each figure.

As illustrated, the towel cabinet preferably consists of an outer frame or section 10 which consists of a bottom 10a, sides 10b, a back 10c, a top 10d having holes 10e cut therein for ventilating purposes, and a front door 10f swinging on hinges 10h, said door consisting of a mirror 10i on the outside, and a mirror backing piece or holder 10j on the inside. The forward edge of the bottom 10a is slightly rearward of the forward edge of the sides 10b, leaving a space 10g between the bottom 10a and the door 10f, through which the toweling runs downwardly out of the cabinet. A large slot 10aa is cut out of the bottom 10a at the rear through which the toweling runs as later described.

When my cabinet is equipped with the automatic take-up mechanism later described, an extension piece 10k, narrower than the width of toweling which passes over it, is attached to the bottom 10a of the outer frame 10, as illustrated in Figure 2 of the drawings. The toweling which passes over this piece 10k is exposed outside of the cabinet so that the user can readily see where to grasp it, and by making said piece 10k narrower than the width of toweling the user can insert his fingers back of the toweling and thereby get a better grip on it than he would be able to if the piece 10k extended to the outer edge of the toweling.

Slidably mounted within this outer frame 10 is an inner case or section 11, having a bottom 11a, sides 11b, a two-piece back 11c, a top 11d, having holes 11e in alignment with

the holes 10e when the inner case is in place. The rear ends 11b of the sides 11b are rearward of the back 11c, and fit flush against the back 10c of the outer frame 10 when the cabinet is in use. This construction of said rear ends 11b provides sufficient space between the back 11c and the back 10c in which the toweling may freely move. This inner case 11 is divided by means of the shelf 12 into a lower compartment 13 in which the roll of clean toweling 14, preferably made of cloth, is inserted, (which roll need not be wound on a stick) and an upper compartment 15 in which the soiled toweling 16 is rolled up on a winding stick. In the simpler form of towel cabinet shown in Figure 1, the front part of the shelf 12 is horizontal while the back part slants diagonally downward so as to provide room for the fingers between it and the driven roll 23 later referred to. This shelf 12 is inserted for the sanitary purpose of separating the soiled toweling from any possible contact with the clean toweling, and when the automatic take-up mechanism is used this shelf may have a gradual slant as shown in Figure 3 of the drawings, allowing sufficient space for the fingers between said shelf 12 and the driver roll 22. A small notch or hole 12a is cut in the front of said shelf 15 in which to catch the end of a chain 43 later referred to. A slot 17 is cut in each side 11b of the inner case 11, and a locking bar 18 extends through these slots with its ends removably mounted in holes 19 cut part way through the sides 10b of the outer frame 10. In one of said holes 19, a finger spring 20 is fitted which is compressed when it is desired to remove the locking bar 18. This locking bar serves to prevent the inner case 11 being accidentally pulled out of the outer frame 10 and the slots 17 are long enough to permit the inner case 11 to be drawn toward the front, part way out of the outer frame, as shown in Figure 4 of the drawings, to make room in the rear for the hands when putting the new toweling in, as later described.

In the lower compartment 13, above the locking bar 18, is a driver control roll 22, and in the upper compartment 15 is a driven control roll 23 of the same construction located in the rear. Each of these control rolls 22 and 23 have a body 24 with an axle 25 extending therefrom, which axle is mounted in ball bearings 25a mounted in holes 26 cut in the sides 11b of the inner case 11. Both of said rolls have a roughened peripheral surface 27 obtained by wrapping sand paper or a sheet of burred metal around the body, or the body 24 may be made of metal roughened on the surface. Within a groove 32, made by cutting from the outside part way through the sides 11b of the inner case, at the end of said rolls 22 and 23, is mounted on each axle 25 a sprocket wheel 28 with teeth 29, on which is mounted a chain 30 which connects both

ratchet wheels 28 which are fixed on the rolls 22 and 23 so that any motion imparted to either roll moves both. Between the two sprocket wheels 28 is a double locking pawl 31, the ends of which fit into the space between the teeth 29 of both wheels 28 and prevent movement in more than one direction, so that the soiled toweling cannot be unwound. This locking pawl 31 is pivoted at 31a off-center towards the driven roll so as to stay engaged in its locking position at all times.

The clean toweling 14 is in direct contact with part of the roughened surface 27 of the driver roll 22 so that as the clean toweling 14 is pulled out this driver roll is caused to rotate, which in turn causes the driven roll 23 to rotate, and this in turn causes the roll of soiled toweling 16, which rests by gravity on the roughened surface 27 of said driven roll 23, to rotate in the opposite direction, thereby winding the soiled toweling 16. A winding stick 36 on which the soiled toweling 16 is rolled, preferably having a portion between its ends cut out to make a flat surface, as clearly shown in Figure 8 of the drawings, is inserted in the loop 37 at one end of the toweling as shown in Figure 9 of the drawings, and then said stick is inserted in the guide slots 11bb cut in the inner case 11, which extend from the front of said case for a short distance horizontally and then diagonally downward so that the stick 36 with the soiled toweling wound around it rests directly on the driven roll 23, and as the soiled toweling 16 becomes larger, the winding stick 36 moves upwardly in the guide slots 11bb.

When it is desired to keep the toweling out of sight, instead of having a loop of it visible as shown in Figure 1 of the drawings, this cabinet previously described is equipped with an automatic take-up mechanism for the soiled toweling. The only toweling then visible is that portion running over the extension piece 10k, just sufficient toweling to see where it is and grasp it. This mechanism is slidably mounted in slots 11bbb cut in the rearward portion of the sides 11b of the inner case 11. In Figure 3 of the drawings this automatic take-up mechanism is clearly shown, which consists of a movable traveler 38 having two sides 39 which slide in the grooves 11bbb and normally rest on the rubber bumpers 11aa at the bottom of the inner case 11 on each side, a top 40 connecting the two sides 39, a traveler roll 41, under which the soiled toweling passes, rotatably mounted in the sides 39 intermediate of their height, an eye 42 attached to the top 40 and a chain 43, one end of which is attached to said eye 42 and the other end having a ring 44a, which chain extends from said top 40 upwardly to the top of the inner case 11 where a small portion is inserted between the outer frame top 10d and the inner case top 130

11d with the ring 44a hanging down in the compartment 15, where it remains while the cabinet is in use. When filling the cabinet this chain 43 is pulled downwardly and the 5 end with the ring 44a is caught in the hole 12a cut in the shelf 12 as shown in Figure 4 of the drawings. When equipped with this automatic take-up mechanism, the inner case 11 is provided with two rotating rolls 44 and 10 45 spaced apart, permanently mounted in the sides 11b near the rear of the inner case 11 over which the soiled toweling 16 passes.

15 It has been found preferable to use lengths of toweling of approximately twenty-five yards, and when more toweling is required a clasp 50 is used to connect two lengths by slipping said clasp into the loops 37 at the end of each length, as shown in Figure 10 of the drawings.

20 The operation of this towel cabinet with the automatic take-up mechanism is as follows:

To insert a roll of clean toweling, the door 10f is opened and the inner case 11 is pulled 25 out as far as the locking bar 18 will permit, as shown in Figure 4 of the drawings. The chain 43 is pulled outwardly and downwardly and caught in the notch 12a in the shelf 12 which causes the traveler 37 to move 30 upwardly as shown in Figure 4 of the drawings. Next a roll of clean toweling 14 is placed in the lower compartment of the inner case and one end, termed the free end, is pulled up and inserted between the locking 35 bar 18 and the driver roll 22 and over the top of said driver roll 22 and down and outwardly through the space 10g. This free end is brought under the cabinet and pushed through the slot 10aa and up the back between 40 the outer frame and inner case and over the two rotating rolls 44 and 45, which brings it under the traveler roll 41, which is now suspended above and between the rolls 44 and 45. The chain 43 is then slipped 45 out of the notch 12a which permits the traveler 37 to drop, and in so doing the traveler roll 41 strikes the toweling and carries it downwardly. Next said free end is pulled outwardly and the winding stick 36 is inserted 50 through the loop 37 formed in said end, and said stick is slipped into the guide slots 11bb and pushed until it drops down and rests on the driven roll 23. The traveler 55 37 now rests on the bumper 11aa at the bottom 11a, and the toweling now runs over the roll 45, which forms a loop, then down and under the traveler roll 41, which forms another loop, and up and over the roll 44 and around the winding stick 36. The inner case 11 is 60 then pushed into the outer frame 10 as far as it will go, the door closed and the cabinet is ready for use. To determine exactly the length of toweling to be unwound from the clean toweling roll 14 in order to make the 65 proper connection with the winding stick 36,

the toweling is marked at a certain point, as by a colored line, and the clean toweling is unwound from the roll 14 until that portion with the colored line on it comes off the roll.

The user, standing in front of the cabinet, 70

grasps the outer edge of that small portion of the toweling which passes over the extension piece 10k, pulls downwardly and outwardly causing it to unwind from the roll of

clean toweling 14, which in turn causes the roll of soiled toweling 16 to wind at the same time the roll 14 unwinds, which pulling may 75

continue until two lengths of toweling, each equal to the distance between the roll 44 and the traveler roll 41, have been unwound from the clean roll and wound on the soiled roll respectively. This winding of soiled toweling 80

lifts the traveler 38 gradually upward until the bottom of the traveler roll 41 is approximately even with the top of the rolls 44 and 45, at which point the limit is reached, the toweling becomes taut, and no further winding or unwinding of either the soiled or 85

clean toweling can take place. This constitutes the measured service whereby each user 90

is limited by each operation of the automatic take-up mechanism to a certain length of toweling. At the same time that the clean 95

toweling is pulled out of the cabinet, a length of soiled toweling not greater than the distance between the roll 45 and the traveler roll 41 is withdrawn from the cabinet, which 100

length furnishes sufficient slack permitting the clean toweling to be freely moved about by the user in drying himself. After the user 105

has dried himself, he releases the toweling, and the traveler 38, which has been held in the position above referred to, immediately drops by gravity to its normal position, and that portion of the toweling which the person has 110

just used is automatically withdrawn inside the cabinet back of the extension piece 10k.

When the last of the roll of clean toweling 115

is used, the door is opened and the winding stick 36, with the soiled toweling wound around it, is slipped out of the guide slots 11bb, and the cabinet again filled with a clean roll.

When the cabinet, without the automatic 120

take-up mechanism, is used, as shown in Figure 1 of the drawings, the roll of clean toweling is inserted the same way, disregarding that part which applies to the automatic mechanism, the free end of toweling being

run under the cabinet and up the back directly onto the winding stick 36, except that allowance must be made between the two rolls of toweling 14 and 16 for a portion of the toweling to hang exposed under the cabinet in a loop 51. Only the toweling which constitutes the front half of the loop 51 is used for 125

wiping, and the measured service consists of this front half, although there is nothing to prevent the user in drying himself, to continuously withdraw all of the clean toweling,

as there is when my automatic take-up mechanism is used.

Even when the cabinet is equipped with this automatic take-up mechanism, it may be disregarded if, for any reason, it is not desired, and the toweling inserted and used just as if the mechanism were not there, leaving a loop 51 hanging below the cabinet.

I claim as my invention:

- 10 1. A towel cabinet comprising an outer frame and an inner case having a forward and backward sliding movement, the side walls of said inner case having substantially horizontal slots therein, a bar extending across said inner case and having its end portions projecting through said slots and fitting within holes provided in said outer frame, said inner case being free to slide on said bar and being limited in its forward and backward movement by said bar, the lower portion of said inner case having a support for a towel supply, a driver roll mounted in said inner case above said towel supply and over which a web of clean towel may be stretched from said supply, a door for the front of said outer frame, an opening being provided in the bottom of the cabinet through which the web of clean towel may be drawn for use.
- 15 2. A towel cabinet comprising an outer frame and an inner case having a forward and backward sliding movement, the side walls of said inner case having substantially horizontal slots therein, a removable bar extending across said inner case and having its end portions projecting through said slots and fitting within holes provided in said outer frame, said inner case being free to slide on said bar and being limited in its forward and backward movement by said bar, the lower portion of said inner case having a support for a towel supply, a driver roll mounted in said inner case above said slots near said bar and rearwardly thereof and whereto the web of clean towel may be stretched from said supply, the bottom of said case having an opening through which the web of towel may depend, the relative position of said bar and driver roll being such that a web may be held by said bar in contact with said driver roll.

- 20 3. A towel cabinet having a support for a towel supply in its lower portion, instrumentalities for feeding the towel outwardly from the cabinet, a wall separating the towel supply from the rear wall of the cabinet to form a narrow vertical gap, the bottom of the cabinet having an opening leading to said gap, guide rolls mounted in said cabinet above said wall and over which the web of soiled towel carried upwardly through said opening may be stretched, a winding stick mounted in said cabinet above said guide rolls, a driven roll mounted for contact with the convolutions of the towel web on said winding stick, a traveler having a vertical movement in said gap

between said guide rolls and under which traveler the web of towel may be stretched, said traveler having a vertical movement to a point above said guide rolls in the rear of said driven roll and means extending to the front of the cabinet within convenient reach of the operator for holding said traveler in its raised position as when the cabinet is being loaded.

4. A towel cabinet having a support for a towel supply in its lower portion, instrumentalities for feeding the towel outwardly from the cabinet, a wall separating the towel supply from the rear wall of the cabinet to form a narrow vertical gap, the bottom of the cabinet having an opening leading to said gap, guide rolls mounted in said cabinet above said wall and over which the web of soiled towel carried upwardly through said opening may be stretched, a winding stick mounted in said cabinet above said guide rolls, a driven roll mounted for contact with the convolutions of the towel web on said winding stick, a traveler extending across the cabinet and having vertical guides in the side walls thereof extending from the bottom of said cabinet to a point above and in the rear of said driven roll, said traveler being adapted to contact with the towel web between said guide rolls and exert a downward pull thereon to draw the towel in to the cabinet, and flexible means connected to said traveler and extending to the top of the cabinet for raising said traveler and holding it in its upper non-working position.
